UNITED STATES PATENT OFFICE.

LOUIS H. THULLEN, OF EDGEWOOD, PENNSYLVANIA, ASSIGNEE TO THE UNION
SWITCH & SIGNAL COMPANY, OF SWISSVALE, PENNSYLVANIA, A CORPORATION
OF PENNSYLVANIA.

ELECTRIC RAILWAY AND SIGNALING SYSTEM THEREFOR.

1,092,411.

Specification of Letters Patent.

Patented Apr. 7, 1914.

Application filed March 3, 1906. Serial No. 303,944.

To all whom it may concern:

Be it known that I, LOUIS H. THULLEN, a citizen of the United States, residing at Edgewood, in the county of Allegheny and

5 State of Pennsylvania, have invented certain new and useful Improvements in Electric Railways and Signaling Systems Therefor, of which the following is a specification.

My invention relates to signaling systems 10 for railways wherein the track rails are divided by suitable insulation to form block sections for signaling purposes and are included in and form part of the return path or conductor to the generator for the current 15 employed for propelling motor vehicles along the railway.

My invention herein relates to means for 20 protecting the inductive bonds or other devices for conducting propulsion current from one block section to another and the electrical apparatus connected with the track rails and included in the signaling system from a dangerous unbalancing of the resistance in the track rails to the flow of propulsion current there along.

I will describe an electric railway and signaling system therefor embodying my invention and then point out the novel features thereof in claims.

30 In the accompanying drawing, Figure 1 is a diagrammatical view of a portion of an electric railway, the track rails of which are divided by insulation to form block sections, of inductive bonds for transmitting 35 the propulsion current from the rails of one block section to another, and a signaling system embodying my invention applied to the railway. Fig. 2 is a detail diagrammatical view of a different form which my invention may assume.

Similar reference characters designate corresponding parts in all of the figures.

Referring now to the drawings, A designates a portion of a railway which is divided 45 into sections, X, Y, Z, etc. These sections are generally termed "block or track sections" and I will hereinafter refer to them as "block sections". These block sections are formed by inserting insulation *a* in 50 some form at determined points in one or both of the traffic rails, the one arrangement being the equivalent of the other so far as block sections is concerned, and both being well known in the art. In the draw-

ing I have shown insulation *a* inserted in 55 both of the traffic rails.

x, x¹; y¹, y; z¹, z, designate the track rails of each block section.

P designates a generator of current for the motor vehicles traveling along the railway. In the drawings I have illustrated the generator as being a generator of alternating current.

T designates a trolley or third rail connected with one pole of the power generator 65 and extending along the railway in a usual and well known manner. The track rails of the railway, one or both, form part of the return path or conductor for the propulsion current employed for the motor cars. 70 The propulsion current is conducted around the points of insulation by means of inductive bonds. Each inductive bond preferably comprises a core and a winding, the bond being of such construction and ar- 75 rangement as to afford a path of low ohmic resistance for the propulsion current. A form of bond which I preferably employ when both of the track rails are divided by insulation is described and illustrated in 80 my co-pending application filed the 27th of February, 1906, Serial No. 303,201, and which is also diagrammatically illustrated in my applications filed February 5th, 1904, Serial Nos. 192,145 and 192,146. These 85 bonds, generally stated, each comprise a laminated iron core which may or may not have an open magnetic circuit depending upon conditions, and a copper winding of a few turns, all the turns being in the same 90 direction and located on the same portion of the core. The ends of a winding of an inductive bond are connected with the track rails of a block section, while a conductor extends from the middle point of the winding, and which conductor is arranged to be connected to the middle point of the winding of an adjacent bond. In the drawing I have diagrammatically illustrated the 95 bonds and their connections.

B, B¹, B², B³, etc., designate the bonds. b designates the core thereof, and b¹ the winding.

b² designates a conductor joining the mid- 100le points of two adjacent coils. This conductor, as will be seen, may be common to two adjacent coils.

The track rails (of the railway) of course,

will be connected to the generator at power stations in the usual and well known manner understood in this art. Thus it will be seen that the current taken from the feed 5 conductor T and after passing through the car motors to the track rails will flow through the track rails and windings of the bonds back to the generator in the direction indicated by the plain arrows. It will be

10 seen that the propulsion current in the passage through the windings of the bonds flows in at their ends and out at their middle points or in at their middle points and out at their ends in reverse or opposite directions, the result being that the cores are 15 not appreciably magnetized, so that the bonds may be used as impedances for alternating signaling currents which may be used in the track circuits. This has been all set 20 forth in my applications hereinbefore referred to, Serial Nos. 192,145 and 192,146.

In the signaling system I employ a track circuit for each block section which, as usual, comprises a source of signaling current, a 25 relay and the track rails of the block section or portions of them, the source of signaling current, relay and track rails being in series circuit. I preferably employ an alternating signaling current in each track circuit and 30 in the event that alternating current is used for propulsion purposes the alternating signaling current of the track circuit is of a different frequency from the frequency of the propulsion current. In any event, the 35 relay or translating device is constructed to respond to control its signal as to one of its movements to the signaling current of the track circuit, or the relay may be protected by apparatus or devices which will prevent 40 its being operated by the car propulsion current.

P^1 designates a generator for alternating signaling current, and p , p^1 , conductors extending therefrom along the line of railway. 45 Q , Q^1 , etc., designate step-down transformers, one being provided for each block section. These transformers are for supplying alternating signaling current to the track circuits of the block sections, and preferably 50 the transformer for each block section will be located at about the middle point of the track circuit of the block section, so that it will supply alternating signaling current to both ends of the track circuit.

55 R , R^1 , etc., designate translating devices or, as I shall hereinafter term them, "relays." Each relay as shown, comprises a field coil r embracing a field and an armature coil r^1 . The field coil is energized by current from one end of the track circuit and the armature coil from the other end of the track circuit and preferably through a 60 step-up transforming device, here shown as a transformer and designated M . When

the field and armature coils are simultaneously energized from the alternating signaling current the armature will be moved in a direction to close a local circuit, and when either or both of the coils are deenergized from any cause, as for example, when the wheels and axles of a car are bridging the track rails of the track circuit, the armature will move to open the local circuit.

A track circuit may be traced as follows, 75 taking as an example the track circuit of the block section Y: Starting from one terminal of the secondary of the transformer Q , one half of the track circuit is wire 1, track rail y , wire 2, field coil r of relay R , 80 wire 3, track rail y^1 , and wire 4 to the other terminal of the transformer. The other half of the track circuit from the secondary of the transformer is wire 1, track rail y , wire 5, a conducting part n^1 of an automatic 85 cut out to be hereinafter described, wire 6, primary of step-up transformer M , wire 7 to track rail y^1 and wire 4. The flow of the signaling current through the track circuits is indicated by the feathered arrows.

The "local circuits" hereinbefore referred to as being controlled by the relays include the operating mechanism of railway signal, should it be an automatically operated signal. This is well understood in 95 the art and will not be further described.

S , S^1 , etc., designate the railway signals which may be any of the well known automatic types. The railway signals are dia- 100 grammatically illustrated as being of the semaphore type.

So far I have merely described the arrangement of the track rails to form block sections and a part of the return path or conductor for the propulsion current and a signaling system which may be employed. The 105 flow of propulsion current to the generator P from the cars is indicated by the plain arrows and the flow of alternating signaling

110 current in the track circuits is indicated by the feathered arrows. No car or train is illustrated, and the circuits of the signaling system and apparatus thereof will be as illustrated. Should a car or train enter a block section, the wheels and axles thereof will short circuit the alternating signaling current of the track circuit of that block section from the field and armature coils, or either one of them, thus causing the armature of the relay to move and open the local

115 circuit of the railway signal to have the signal device thereof move to its danger position. This condition of the circuits and apparatus will remain so long as the car or train remains in the block section. After the car or train moves out of the block section the alternating

120 signaling current again energizes the coils of the relay to have its armature again move to close the local circuit of the railway signal so as to have the signal device move

125 130 135 140 145 150 155 160 165 170 175 180

to its clear position. Thus it will be seen that when no car or train is in a block section, the alternating signaling current of the track circuit of that block section energizes its relay to have it control the railway signal as to one of its operations, and when the alternating signaling current is shunted from the relay, as for example by the wheels and axles of a car or train, the relay being deenergized, its armature moves to open the local circuit of the relay to have the railway signal again operate to give another indication, usually a danger indication. Thus it will be seen that the relay responds to control a railway signal to the absence or presence, so to speak, of the energizing effect of the alternating signaling current. This is all well understood in the art. The construction of the impedance bonds and the electrical apparatus connected with the track rails is such that any reasonable unbalancing of the resistance in the track rails to which they are connected, will not affect the bonds in their function as impedances to the alternating signaling current or the electrical apparatus. In short, the bonds and electrical apparatus are constructed to meet the usual conditions. Should, however, there be any dangerous unbalancing of the resistances in the track rails at any point due to a broken rail, or very poor bonding between the rail sections of one track rail, or the interposition of a high resistance in one of the track rails or the disconnection of one terminal of a winding of an inductive bond in the block section, or from any other abnormal cause, the propulsion current might affect the bonds or apparatus to have them operate improperly. A dangerous unbalancing of the resistance in the track rails in the form of invention illustrated at a point in a block section causes more of the propulsion current to flow through one half or part of the winding of one or both impedance bonds of the block section, thus causing magnetization of the cores and thereby impairing their efficiency as impedances to the alternating signaling current. When this occurs, where A. C. propulsion current is used on the track rails, the impedance bonds of the block section act as auto-transformers and a high potential or voltage is created at the terminals of their windings which tends to apply a greater voltage and current to the electrical apparatus connected with the track rails, which would be seriously detrimental to such electrical apparatus. For example, suppose the rail y of block section Y to be broken at the point designated by the arrow N, or there was a high resistance or some other trouble in the rail y at that point, which prevented or largely retarded the flow of the car propulsion current along that rail, then it will be seen that the greater portion of the propulsion current would tend to flow

through the lower half of the winding of the bond B^1 and along rail y^1 and the lower half of the winding of the bond B^2 at the other end of the block section to the next impedance bond B^3 . The current thus generated by the winding B^1 would flow in a circuit which may be traced as follows: from one end of the winding of bond B^1 , through wire 10, track rail y , wire 2, coil r , wire 3, rail y^1 , and wire 11 to the other end of the winding. The current flowing, caused by the potential at the terminal of the impedance bond B^2 , under the conditions stated, would flow in a circuit which may be traced as follows: from one end of the winding of the bond B^2 through wire 12, track rail y , wires 5 and 6, primary of transformer M, wire 7, track rail y^1 and wire 13 to the other end of the winding. The currents flowing in these circuits will be of a higher voltage than that required of the current to operate the electrical apparatus.

My present invention is to prevent injury to the inductive bond and electrical apparatus connected with the track rails of a block section should this dangerous unbalancing of the resistance occur in the track rails of a block section. I accomplish this by what I term an automatic cut out which is preferably electrically controlled or operated, or electrically controlled and operated. N' , designates such a device. In the drawing I have shown one such device adjacent each inductive bond. This automatic cut out acts when there is a dangerous unbalancing of the car propulsion current in the track rails of a block section to short circuit the bond (establish a short circuit between the track rails) and to either open the local circuit of the railway signal to have it give a danger indication, open the circuit of the relay to deenergize it, in which case it will open the local circuit of the railway signal to have the railway signal give a danger indication, or otherwise affect the railway signal to have it give a danger indication.

As shown in Figs. 1 and 2, the automatic cut out comprises an electro-magnetic device n , and a part n^1 , which is in effect a circuit controller, and when operated by the electro-magnetic device opens a local circuit of a railway signal (see the device N' adjacent the bonds B^1, B^3) or the circuit of the armature of the relay (see the device N' adjacent the bonds B, B^2, B^4) and to close a short circuit on the bond. The electro-magnetic device n is shown as a solenoid and the part n^1 as a conductor moving between two sets of contact points. I do not wish to limit myself to any particular form of automatic cut out and the form of device shown is diagrammatic. Any form of device may be employed which acts when there is a dangerous unbalancing of resistance between the rails of a block section to short circuit the

bond (or establish a short circuit across the track rails adjacent the point of dangerous unbalancing) and relieve the electrical apparatus connected with the track at that 5 point from the effects of the dangerous unbalancing and also cause some indication of the dangerous state of affairs.

The electro-magnetic device n is included in a shunt circuit with a winding of an inductive bond, such circuit including the winding of the bond, wires 15 and 16, and the winding of the electro-magnetic device. The conducting part n' moves between contact points 20, 21, 22, 23, and the part n' 10 when against the points 20, 21, forms part of either the local circuit of a railway signal or part of the track circuit as the case may be. The part n' when against the contact points 22, 23, forms part of a short circuit 15 for the impedance bond with which it is associated. This short circuit may be traced as follows: from one track rail of a block section to wire 15, a few turns of the electro-magnetic device, wire 30, contact points 22, 25 23 and part n and wire 16 to the other track rail of the block section. Thus it will be seen that when the part n' is against the contacts 22, 23, it is held in that position by reason of the circuit including a few turns of 30 the electro-magnetic device.

In Fig. 2, I have shown a modification of my invention. The electro-magnetic device n or some of the turns thereof is included in a circuit with a winding n' provided on the core of a bond. In this arrangement each bond is in effect, under the dangerous conditions above stated, a transformer. The short circuit for the bond is the same as described in connection with Fig. 1. Thus in 35 this form when there is a dangerous unbalancing of the resistance in the track rails of a block section, the inductive bond adjacent that point acts on the adjacent device N' and a short circuit is established around the 40 bond, thereby saving it from the action of the high potential due to the unbalancing of the resistance of the rails.

In the usual operation of the system, the devices N' are wound or arranged so as not 45 to be operated by the ordinary unbalancing of resistance in the track rails, that is, they are not operated under the usual conditions, and are only operated where there is a dangerous unbalancing of the resistance.

Instead of having the part n' open the local circuit of the railway signal or the circuit of the relay, it may only establish a short circuit across the track rails of the block section, which being of lower resistance than other circuit in the block section, permits of all currents in the track rails adjacent the short circuit flowing through it rather than the other circuits and the electrical apparatus in such circuits connected 60

with the track rails at that point. Also there 65 may be only one automatic cut out for each block section which may be operated from one or both of the inductive bonds to establish a short circuit across the track rails of the block section when there is a dangerous 70 unbalancing of the resistance in the track rails of a block section due to any abnormal cause, which short circuit may alone affect the railway signal of the block section to give a danger indication or the automatic 75 cut out upon its operation may be made to affect the railway signal to have it give a danger indication.

What I claim as my invention is:

1. The combination with the track rails 80 of a railway both of which are divided into block sections by insulation and conduct propulsion current in one direction and a signaling current in opposite directions, inductive bonds for conducting the propulsion 85 current from the track rails of one block section to another, and means adjacent each inductive bond and operated upon an unbalancing of the resistance in the rails for establishing a short circuit across the rails 90 of the block section.

2. The combination with the track rails of 95 a railway both of which are divided into block sections by insulation and conduct propulsion current in one direction and a signaling current in opposite directions, inductive bonds for conducting the propulsion 100 current from the track rails of one block section to another, a railway signal for each 105 block section, and means in each block section for establishing a short circuit across the track rails of the block section where there is a dangerous unbalancing of the resistance of such rails and for affecting the railway signal to have it give a danger indication.

3. The combination with the track rails of 110 a railway divided by insulation to form block sections for signaling purposes and conducting power current, inductive bonds 115 in the track for conducting the power current around insulation points, railway signals, and means operated upon a dangerous unbalancing of the resistance in the track rails for establishing short circuits around 120 the bonds adjacent the point of dangerous unbalancing and to affect a railway signal adjacent the same point to give a danger indication.

4. The combination with the track rails of 125 a railway divided by insulation to form block sections for signaling purposes and conducting power current, inductive bonds 125 in the track for conducting the power current around insulation points, railway signals, and means including an electro-magnetic device operated upon a dangerous unbalancing of the propulsion current in the

track rails for establishing short circuits around the bonds adjacent the point of dangerous unbalancing and to affect a railway signal adjacent the same point to give a danger indication.

5. The combination with the track rails of a railway divided by insulation to form block sections for signaling purposes and conducting power current, inductive bonds 10 in the track for conducting the power current around insulation points, railway signals, and means in each block for controlling the potential at the inductive bonds produced by the power current and due to unusual 15 resistance in one of the track rails.

6. The combination with the track rails of a railway divided by insulation to form block sections for signaling purposes and conducting power current, inductive bonds 20 in the track for conducting the power current around insulation points, railway signals, means in each block for controlling the potential at the inductive bonds produced by the power current and due to unusual 25 resistance in one of the track rails, and for causing an operation of a railway signal to give a danger indication when such potential occurs.

7. In a signaling system for electric railways 30 ways both lines of rails of which are included in the circuit of the propulsion current and are divided by insulations to form block sections, inductive bonds for conducting the propulsion current from the track 35 rails of one section to the track rails of an adjacent section, and means adjacent each inductive bond and operated upon an unbalancing of the resistance of the track rails for establishing a short circuit across the 40 rails of the block section.

8. In a signaling system for electric railways 45 both lines of rails of which are included in the circuit of the propulsion current and are divided by insulations to form block sections, means for conducting the propulsion current from the track rails of one block section to the track rails of an adjacent section, and means for each section 50 operative upon a dangerous unbalancing of the flow of propulsion current in the track rails of such section for short-circuiting the track rails of such section.

9. In a signaling system for electric railways 55 both lines of rails of which are included in the circuit of the propulsion current and are divided by insulations to form block sections, inductive bonds for conducting the propulsion current from the track rails of an adjacent section, and means adjacent each bond and operative upon a dangerous 60 unbalancing of the flow of propulsion current through the bond for short-

circuiting the track rails of the corresponding block section.

10. In a signaling system for electric rail- 65 ways both lines of rails of which are included in the circuit of the propulsion current and are divided by insulations to form block sections, inductive bonds for conducting the propulsion current from the track 70 rails of one section to the track rails of an adjacent section, and means for each section operative upon a dangerous unbalancing of the resistance of the track rails of such section for short-circuiting the track 75 rails of such section.

11. In a signaling system for electric rail- 80 ways both lines of rails of which are included in the circuit of the propulsion current and are divided by insulation to form 85 block sections, means for conducting the propulsion current from the track rails of one block section to the track rails of an adjacent block section, and electromagnetic means for short-circuiting the track rails 90 of a block section when a dangerous unbalancing of the flow of propulsion current occurs in the track rails of such a section.

12. In combination, an electric railway 95 the track rails of which are included in the circuit of the propulsion current, and means responsive to a predetermined difference of potential of the propulsion current in the track rails for establishing a connection across the track rails.

13. In combination, an electric railway 100 the track rails of which are included in the circuit of the propulsion current, and are divided to form block sections, signals for the block sections, means for conducting 105 propulsion current from the track rails of one block section to the track rails of another block section, and means for each block section responsive to a predetermined difference of potential of the propulsion 110 current in the track rails of the block section for causing the signal for that block section to indicate danger.

14. In combination, an electric railway 115 the track rails of which are included in the circuit of the propulsion current, a normally open connection across the track rails, and a relay connected across the track rails and responsive to a predetermined difference of potential of propulsion current in the track rails for closing said connection.

In testimony whereof I have signed my name to this specification in the presence of two subscribed witnesses.

LOUIS J. THULLEN.
